UNITED STATES PATENT OFFICE

149,595

DESIGN FOR A STUFFED KOALA BEAR

Clara B. Tomaszewski, Brooklyn, N. Y.

Application November 20, 1946, Serial No. 134,953

Term of patent 3½ years

(Cl. D34—2)

To all whom it may concern:

Be it known that, Clara B. Tomaszewski, a citizen of the United States of America, residing at Brooklyn, in the county of Kings, and State of New York, has invented a new, original, and ornamental Design for Stuffed Koala Bear, of which the following is a specification, reference being had to the accompanying drawing, forming part thereof.

I claim:

The ornamental design for a stuffed koala bear as shown.

CLARA B. TOMASZEWSKI.
